UNITED STATES PATENT OFFICE

CLEMENT BOOTH, OF CINCINNATI, OHIO, ASSIGNOR, BY MESNE ASSIGNMENTS, TO THE
HEALD MACHINE COMPANY, OF WORCESTER, MASSACHUSETTS, A CORPORATION OF
MASSACHUSETTS

GRINDING MACHINE

Application filed October 25, 1930. Serial No. 491,123.

This invention relates to improvements in an apparatus for grinding and finishing and especially to improvements in a grinding machine for supporting, rotating and grinding a work piece such as a bearing roll for antifriction bearings and the like.

One of the principal objects of the present invention is the provision of a machine for accurately and expeditiously grinding the terminal portion of cylindrical parts such as bearing rolls for antifriction bearings or the like.

Another object of the invention is the provision of a machine especially adapted for the grinding or forming of the terminus or seat portion of tapered antifriction rolls so that a series of such rolls will have their seat portion in a definite relation to the body portion thereof whereby the several rolls when mounted in a single bearing will bear the proper relation to one another and to the bearing race to properly distribute the bearing load and thereby increase the life and usefulness of the bearing.

Another object of the present invention is the provision of an improved machine for finishing, grinding and forming the terminal portion of taper antifriction bearing rolls normal to the axis of rotation of such tapered members.

Another object of the invention is the provision of improved means for supporting and rotating normally difficult to handle work pieces, such as tapered antifriction bearing rolls, without the use of chucks or the like and for presenting said work pieces while being so supported and rotated to the action of a cutting tool.

Other objects and advantages of the present invention should be readily apparent by reference to the following specification considered in conjunction with the accompanying drawings forming a part thereof, and it is to be understood that any modifications may be made in the exact structural details there shown and described, within the scope of the appended claims, without departing from or exceeding the spirit of the invention.

In the drawings:

Figure 1 is a front elevation of a grinding

machine embodying the improvements of this invention.

Figure 2 is a top plan view of the machine shown in Figure 1.

Figure 3 is an enlarged fragmentary sectional view taken on line 3—3 of Figure 1.

Figure 4 is a fragmentary sectional view of certain parts shown in Figure 3 but bearing a different relation to one another.

Figure 5 is a top plan view of a modified form of mechanism embodying the principles of the invention, certain parts of which are shown in cross section.

Figure 6 is a sectional view on line 6—6 of Figure 5.

Figure 7 is a developed sectional view on line 7—7 of Figure 6.

Throughout the several views of the drawings similar reference characters are employed to denote the same or similar parts.

This invention finds its principal use in grinding the terminal seat portion of tapered anti-friction bearing rolls normal to the axis of rotation of such rolls. The device, as shown in Figures 1 to 4 inclusive, may comprise a bed 10 having a column 11 rising thereabove and to one side thereof. The column is provided with a dove-tailed guide 12, Fig. 2, received in a similarly formed guideway 13 provided in a carrier 14. An elevating screw 15 may be provided for adjusting the carrier 14 relative to the column 11 which may be operatively coupled with the hand wheel 16, Fig. 2, for actuation thereby.

The carrier 14 is provided with arms 17 and 18 receiving therebetween a tang 19 extending from a motor housing 20. The arms 17 and 18 and the tang 19 are provided with bores in axial alignment with one another for an axle bolt or the like 21. Nuts 22 on one end of axle bolt 21 and the head 21a thereof cooperate with one another to secure the carrier and motor housing in angular relation relative to one another for a purpose that will later appear. The motor housing 20 has extending from it a spindle 23, Fig. 1, to which is secured a grinding wheel 24 rotatable at a high or grinding rate of speed by the motor 20.

Referring to Figs. 2 and 3, the upper por-

tion of the table 10 has secured thereto a pair of similar bed plates 25 and 26, Fig. 3, each having formed therein a guideway 27 and 28 respectively receiving the dove-tailed 5 tongues 29 and 30. The tongues 29 and 30 respectively, depend from slides 31 and 32 each being in turn provided with a dove-tailed groove 33 and 34 receiving similarly formed tongues 35 and 36 depending from 10 slides 37 and 38 super-imposed on the slides 31 and 32. Intermediate the plates 25 and 26 and carried by the bed 10 is a pressure or guide bar 39 having opposite faces 40 and 41 angled relative to one another and the said 15 faces extend downwardly in opposite directions.

The angular or tapered faces 40 and 41 are respectively adjacent to and spaced from angular faces 42 and 43 formed respectively 20 on the slides 35 and 36. The said faces 40 and 42 and 41 and 43 form between them work receiving grooves having an included angle of the same degree as the work to be operated upon. By reference to Figure 3 25 it will be noted that the size or width of the work receiving grooves is such that the work after being positioned therein extends above the upper surface of the slides 35 and 36 and pressure bar 39 so that the grinding wheel 24 may act on the said projecting portion. The work is adapted to be actuated along the upper portion of the bed 10 through the work receiving grooves beneath the grinding wheel to have an operation performed thereon.

30 In practice one set of slides is being utilized to actuate or traverse the work relative to the grinding wheel while the other set or pair of slides is being returned from the unloading position to the loading position. For example, and as shown in the drawings, slides 31 and 37 are traveling to the left, as seen in Figures 1 and 2, for traversing the work pieces carried thereby relative to the grinding wheel while the slides 32 and 38 are 35 moving from the left, or unloading position, to the right to receive a series of unfinished work pieces, which latter are manually positioned in the work supporting structure at the right end of the machine. For effecting 40 this movement the slides 31 and 37 are each provided on their outward faces with rack teeth 45 and 46, Fig. 3, respectively meshing with gears 47 and 48 of compound gear 49. The gears 47 and 48 are of an unequal number of teeth, the former having one tooth more than the latter whereby a slight differential movement is obtained between the slides 31 and 37 whereby slide 37 moves slightly faster than slide 31. Slide 31 has secured 45 to it for movement therewith work rest blades 50 which back up the work to take the thrust of the grinding wheel on the work and to prevent canting or tilting thereof in the work throat. The differential movement between 50 the slides results in a slightly slower move-

ment of the blades 50 than the normal roll of the work as obtained through the opposed tapered faces 40 and 42 of the pressure bar 39 and slide 37 respectively.

As has been noted above, the angle of the 70 faces 40 and 42 relative to one another is equal to the taper on the work whereby the work rolls on its prefinished surface about its normal axis and since the grinding wheel operates in a plane at right angles to the axis 75 of the work the end or seat portion thereof is finished or ground normal to the said axis.

The slides 32 and 38 are likewise each provided with rack teeth 51 and 52 meshing with gears 53 and 54 of compound gear 55. The 80 same relation between gears 53 and 54 exists as there is between gears 47 and 48, so that the same differential of movement between the slides 32 and 38 is obtained.

The compound gear 49 is secured to a stud 85 56 rotatably journaled in the bed plate 25 and has secured thereto a bevel gear 57 meshing with a similar bevel gear 58 fast on driving shaft 59. The compound gear 55 is similarly secured to a stud 60 journaled in the bed 90 plate 26 and has secured to its one end a bevel pinion 61 meshing with a similar bevel gear 62 fast on the driving shaft 59. By reference to Figure 3 it will be noted that the slides 31 and 37 have their teeth formed on the 95 sides thereof opposite to the sides of the slides 32 and 38 on which their rack teeth are formed, so that rotation of the compound gears 49 and 55 in the same direction will reciprocate their respective slides in opposite directions whereby one set of slides is traversing the work against the action of the grinding wheel while the remaining set is being returned to the loading station.

The driving shaft 59 is mounted in suitable bearings formed in the walls of the bed 10 and the said shaft 59 has secured to its forward end a gear 63 meshing with change gears or the like 64 which extend to a suitable initial driver or prime mover for effecting a rotation of the shaft 59. A suitable housing or guard 65 may be provided for enclosing the gears 63—64 and the like.

The foregoing description deals with the 115 normal operation of the machine for producing flat seats or terminal portions on tapered work pieces which are at right angles to the axis of rotation thereof. By adjusting the motor 20 and grinding wheel 24 about the axis of axle bolt 21 crowned or contoured 120 terminal portions may be provided on the work. For this purpose the slide 37 is formed with a depression 66 to form a clearance for the end of the wheel when it is tilted, as shown in Figure 4, in which position a crown, as 125 there shown, may be formed on the work or the seat or terminus of the work may be contoured by removing the corner of the work and forming a flat portion between the body and the flat top surface of the work.

The structure shown in Figures 5, 6 and 7 is of a slightly different form in that instead of actuating the work pieces tangentially of the wheel the work is actuated in a circular 5 path relative to the grinding wheel. For this purpose a bed 67 is provided supporting a stationary shaft 68 having secured to its upper end a plate 69, the peripheral face 70 of which is tapered or formed in accordance 10 with the taper or form of the work to be operated upon. A stationary bearing portion 71 is carried by the bed 67 and has secured therein the stationary shaft 68. Supported by the bearing portion 71 is a rotatable member 72 having a flange 73 extending from one end thereof, in the periphery of which are formed gear teeth 74 meshing with a pinion 75 secured to one end of a shaft 76 journaled in a boss 77 carried by the bed 67. 15 Secured to the other end of shaft 76 is a second pinion 78 meshing with an idler gear 79 rotatably journaled on the stationary shaft 68. The idler gear 79, in addition, meshes with the teeth of a drive pinion 80 fast on a 20 driving shaft 81 journaled in a second boss 81a carried by the bed 67. A pulley 82 is secured to the shaft 81 whereby motion and power are transmitted to the said shaft. 25 The rotatable member 72 has extending 30 above the flange 73 a circular body or bearing portion 83 about which is encircled a work rotating or driving ring 84 having a flange 85 resting on the upper bearing surface of flange 73. The work rotating ring 35 84 is provided on its upper end with a flange 86 in which are formed gear teeth 87 meshing with a pinion 88 fast on the upper end of drive shaft 81. The work driving ring 84 extends above the upper limits of the rotatable member 72 and has its inner edge 89 spaced from the tapered face 70 of plate 69 and the said inner edge 89 is tapered oppositely to the taper on face 70 and cooperates therewith to form a work receiving trough 45 having an included angle corresponding to the work to be operated upon. 50 In order to prevent the work pieces from tilting or canting while in the work groove the said work is backed up by backing up members or blades 90 which are carried by the rotatable member 72. In order to maintain a sufficient back pressure between the work and the backing up members or blades 90 the gears 87 and 74 are made of an unequal number 55 of teeth whereby the gear 74 is driven at a slightly slower rate than the gear 87 so that the backing up members or blades 90 tend to hold the work against their natural roll as effected through the engagement of tapered face 70—89 therewith. In other words a slight back pressure is maintained between the work and blades 90 which prevents the work from tilting or canting in the work receiving trough and the work blades 90 take the thrust of the grinding wheel during 60 the grinding operation. The differential rotation of the member 72 and work rotating ring 84 is obtained, as noted above, through the unequal gears 74 and 87 which gears are respectively driven by pinions 75 and 78 driven at the same rate of speed through the pulley 82 and interconnecting gears. 65 The work pieces may be dropped into the work receiving groove by any desirable means ahead of the backing up members or blades 90 and actuated relative to the grinding wheel to effect a stock removal therefrom. In order to discharge the work pieces from the trough at the conclusion of the grinding operation the rotating member 72 is provided with a plurality of apertures 91 therein, Fig. 7, each aperture being adjacent the work engaging face of the backing up members 90. An ejector pin 92 is provided in each aperture 91 directly beneath each work piece and the lower end 93 of each pin rides on the upper surface 94 of cam track 95. The said track 95, as seen in Figure 6, is secured to the stationary bearing portion 71 beneath the path of movement of the said pin and the track is provided with an inclined cam portion 96 whereby the said ejector pins are forced outwardly through the apertures 91 for effecting an ejection of the work from the work receiving trough, as best shown in Fig. 7. The cam portion 96 is positioned adjacent the operator's station so that the work may be readily withdrawn from the machine following ejection from the work receiving trough and a new work piece inserted therein. 95

From the foregoing it will be noted that tapered bearing rolls or the like, may be expeditiously and accurately formed as to their seat portion which is formed absolutely normal to the axis thereof since the work is floated and rotated on the ultimate bearing face and the seat portion formed in accordance with and relative to the bearing thereof. 100

What is claimed is:

1. In a grinding machine of the class described, the combination of a bed, a grinding wheel carried by the bed, a work receiving trough carried by the bed comprising a fixed side secured to the bed and a movable side spaced from the fixed side forming the work receiving trough therebetween in which the work is disposed in simultaneous engagement with the sides of the trough, means for actuating the movable side and rolling the work on the fixed side relative to the grinding wheel, and additional means in the work receiving trough laterally engaging the work to take the thrust of the grinding wheel, said last means being movable to maintain engagement between said means and the work as the latter is rolled by the movable side. 110
2. In a grinding machine for grinding the 115
- 120
- 125
- 130

- terminal seat portion of tapered bearing rolls, the combination of a bed having a work supporting portion, a grinding wheel carried by the bed and rotatable in a horizontal plane above the work supporting portion, means for supporting and rotating taper rolls and laterally actuating same relative to the grinding wheel to effect stock removal therefrom comprising a fixed plate having a tapered face and a rotatable plate having a moving face opposed to the face of the fixed plate and forming a work receiving groove therebetween, and means in the work receiving groove for engagement with the work to take the thrust of the grinding wheel. 5
3. In a grinding machine of the class described the combination of a bed having a work supporting portion, a grinding wheel carried thereby and rotatable in a horizontal plane above the work supporting portion, a stationary bar carried by the bed beneath the plane of rotation of the grinding wheel, a slide carried by the bed for movement relative thereto and spaced from the stationary bar to form a work receiving groove, the opposed faces of the groove conforming to the contour of the work to be received thereby, means for translating the slide for effecting a rotation of the work about its axis through the frictional contact of the work and the slide, and means laterally engaging the work to prevent tilting or canting of the work in the work receiving groove and to take the thrust of the grinding wheel on the work. 10
4. In a grinding machine of the class described the combination of a bed having a work supporting portion, a grinding wheel carried thereby and rotatable in a horizontal plane above the work supporting portion, a stationary bar carried by the bed beneath the plane of rotation of the grinding wheel, a slide carried by the bed for movement relative thereto and spaced from the stationary bar to form a work receiving groove, the opposed faces of the groove conforming to the contour of the work to be received thereby, means for translating the slide for effecting a rotation of the work about its axis through the frictional contact of the work and the slide, means laterally engaging the work to prevent tilting or canting of the work in the work receiving groove and to take the thrust of the grinding wheel on the work, a second slide beneath the work rotation slide for supporting and translating the grinding wheel thrust members, and means for translating the second slide. 15
5. In a grinding machine for grinding and forming the terminal seat portion of tapered anti-friction rolls the combination of a grinding wheel, a support therefor, means rotatably supporting and actuating a series of work pieces tangentially of the grinding wheel including a fixed bar, a slide adjacent thereto and spaced therefrom forming a work re-
- ceiving trough, means for effecting translation of the slide for actuating the work, and means for adjusting the angular relation between the grinding wheel and work groove for forming the terminal seat portion of the work. 20
6. In a grinding machine for grinding the terminal seat portion of tapered anti-friction bearing rolls the combination of a grinding wheel, a support for the grinding wheel, a work receiving trough carried by the bed comprising a fixed side secured to the bed, a movable side journaled on the bed, the opposed sides of the trough conforming substantially to the work to be operated upon, and work blades within the trough laterally engaging the work to prevent canting of the work in the trough and to take the thrust of the grinding wheel. 25
7. In a grinding machine for grinding the terminal seat portion of tapered anti-friction bearing rolls the combination of a grinding wheel, a support for the grinding wheel, a work receiving trough carried by the bed comprising a fixed side secured to the bed, a movable side journaled on the bed, the opposed sides of the trough conforming substantially to the work to be operated upon, work blades within the trough laterally engaging the work to prevent canting of the work in the trough and to take the thrust of the grinding wheel, means supporting the work blades for movement in the direction of the movement of the work, and means for shifting the work and blades at differential speeds to maintain a certain backing up pressure between the work and blades. 30
8. In a grinding machine for grinding the terminal portion of cylindrical articles comprising means for laterally frictionally engaging the articles and movable relative to the articles, means for actuating the laterally engaging means for rolling the articles at a pre-determined rate, a grinding wheel for operation on the terminal portion of the articles while being actuated, and additional lateral support means for engaging the work and movable relative thereto at a rate slightly in excess of the rate of movement of the article to exert a backing up pressure on the articles while being ground. 35
9. In a grinding machine for grinding the terminal portions of cylindrical articles, the combination of a grinding wheel, a work receiving trough adjacent the grinding wheel comprising a pair of opposed side members having their opposed faces conforming to the contour of the articles to be ground, a slide for one of the trough faces, means for translating said trough face relative to the remaining face, a second slide movable relative to the first slide, and means carried by the second slide projecting into the work receiving trough for laterally engaging the work therein to take the thrust of the grinding wheel. 40

10. In a grinding machine for grinding the terminal portions of cylindrical articles, the combination of a grinding wheel, a work receiving trough adjacent the grinding wheel comprising a pair of opposed side members having their opposed sides conforming to the contour of the articles to be ground, a slide for one of the trough faces, means for translating said trough face relative to the remaining face, a second slide movable relative to the first slide, means carried by the second slide projecting into the work receiving trough for laterally engaging the work therein to take the thrust of the grinding wheel, and a common actuating means for actuating the two slides at differential rates whereby a pressure is maintained on the work by the means projecting into the work trough and engaging the work.
- 20 11. In a grinding machine for grinding the terminal portions of cylindrical articles, the combination of a grinding wheel, a work receiving trough adjacent the grinding wheel comprising a pair of opposed side members having their opposed faces conforming to the contour of the articles to be ground, a slide for one of the trough faces, means for translating said trough face relative to the remaining face, a second slide movable relative to the first slide, means carried by the second slide projecting into the work receiving trough for laterally engaging the work therein to take the thrust of the grinding wheel, a common actuating means for actuating the two slides at differential rates whereby a pressure is maintained on the work by the means projecting into the work trough and engaging the work, said means comprising a rack on each slide, a gear for each rack, said gears each having a different number of teeth, and a common shaft for rotating the gears.
- 25 12. In a grinding machine for grinding the terminal seat portion of anti-friction bearing rolls, the combination of a bed, a grinding
- 5 70 wheel rotatably carried thereby, a work receiving trough adjacent the operative surface of the wheel comprising a fixed side, a movable side, an ejector pin beneath each work piece, and means for axially shifting the pin to eject the work piece from the trough at the conclusion of the grinding operation.
13. In a grinding machine for grinding the terminal seat portion of tapered anti-friction bearing rolls the combination of a bed, a grinding wheel carried thereby and rotatable in a horizontal plane, a work receiving trough below the plane of the grinding wheel and comprising means for rolling the work on its periphery below and in contact with the grinding wheel, means in the trough backing up the work to take the thrust of the grinding wheel thereon, a slide for said backing means, and means carried by said slide for ejecting the work from the grinding throat at the conclusion of the grinding operation.
14. In a grinding machine for grinding the terminal seat portion of tapered anti-friction bearing rolls the combination of a bed, a grinding wheel carried thereby and rotatable in a horizontal plane, a work receiving trough below the plane of the grinding wheel and comprising means for rolling the work on its periphery below and in contact with the grinding wheel, means in the trough backing up the work to take the thrust of the grinding wheel thereon, a slide for said backing means, means carried by said slide for ejecting the work from the grinding throat at the conclusion of the grinding operation, said means comprising an ejector pin slidably carried by the slide at a point adjacent the backing up members, and a fixed cam in the path of movement of the slide and trough for axially shifting the pin and ejecting the work.

In testimony whereof I affix my signature.

CLEMENT BOOTH. 110
